AUTOMOBILE MEDALLION

Perry E. Allen, Detroit, Mich.

Application May 13, 1954, Serial No. 30,486

Term of patent 3½ years

(Cl. D14—6)

FIG. 1

FIG. 2

FIG. 3

FIG. 4

To all whom it may concern:

Be it known that I, Perry E. Allen, a citizen of the United States, residing in Detroit, county of Wayne, and State of Michigan, have invented a new, original, and ornamental Design for an Automobile Medallion, of which the following is a specification, reference being made to the accompanying drawing, in which drawing:

Fig. 1 is a front elevational view of an automobile medallion embodying my new design.

Fig. 2 is a rear elevational view thereof.

Fig. 3 is a section taken on the line 3—3 of Fig. 2.

Fig. 4 is a side elevational view thereof.

I claim:

The ornamental design for an automobile medallion, as shown.
